UNITED STATES PATENT OFFICE

144,687

DESIGN FOR A FILM SPLICER

Jack Briskin, Chicago, Ill., assignor to Revere Camera Company, Chicago, Ill., a corporation of Delaware

Application December 7, 1945, Serial No. 124,463

Term of patent 14 years

(Cl. D61—1)

To all whom it may concern:

Be it known that I, Jack Briskin, a citizen of the United States and a resident of Chicago, in the county of Cook and State of Illinois, have invented a certain new, original, and ornamental Design for a Film Splicer, of which the following is a specification, reference being had to the accompanying drawings, forming part thereof, in which,

Fig. 1 is a side elevation of a film splicer embodying my new design;

Fig. 2 is a plan view thereof;
Fig. 3 is a right end view thereof;
Fig. 4 is a left end view thereof; and
Fig. 5 is a rear elevation.

I claim:
The ornamental design for a film splicer, substantially as shown.

JACK BRISKIN.
